Washington L. Pearsall & Sylvester W. Pearsall of New York, N.Y.
Letters Patent No. 538. Dated Dec 21. 1832.

The schedule referred to in these Letters Patent and making part of the same.

To all to whom these Presents may come:

Be it known that we Washington L. Pearsall, and Sylvester W. Pearsall, of the City, County and State of New York, have invented a new and original design for a Spittoon,

Des. 538

and we do hereby declare that the following is a full, clear and exact description of the same, reference being had to the annexed drawing making part of these presents, in which Fig. 1. is a side elevation shewing the exterior form and Fig. 2. is a vertical section of this design for a spittoon.

a. is the base formed as a hexagon, with the flat inclined sides b. forming a truncated pyramid, within which is the cup or receptacle c. for the saliva d. is a movable cap formed dishing with the inclined edges as shew; this shape forming a neat and plain design, the ornaments painted or attached on the surface being entirely according to the taste of the workman; the design of the shape & configuration being the point of novelty.

We claim the design of the shape and configuration of spittoon shew in the drawing. -

In witness whereof we have hereunto set our signatures this sixth day of November one thousand eight hundred and fifty two.

Witnessed,

Samuel W. Scovell

Charles Seneffent
